SEAT SPRING ARRANGEMENT
Charles S. Viall, Sr., 11313 Chadsey Drive,
Whittier, Calif.

Continuation of application Ser. No. 127,619, July 28, 1961. This application Mar. 6, 1964, Ser. No. 350,100

11 Claims. (Cl. 267—108)

This application is a continuation of my copending application Serial No. 127,619, filed July 28, 1961, for Seat Spring Arrangement, and now abandoned.

This invention pertains to an arrangement for supporting the seat cushion of a chair, sofa or the like.

This spring support arrangement provides a design of the same general type as illustrated in Patents 2,437,119 and 2,485,650. However, in these prior units difficulty has been encountered due to stress concentration in the lower leg of the rear spring, resulting in premature crystallization and failure of this part. This invention overcomes such limitation by the use of a pivotal connection at the bottom portion of the leg for the rear spring. Also, the present invention can be constructed to balance twisting forces on the spring coils, giving greater strength to the coil and increased lateral stability to the seat platform. In addition, this invention provides an improved attachment for the upper spring leg, giving it a rigid connection to the support frame by means of a single clamping member. This invention also permits a platform type cushion support to be utilized in seats intended for more than one person. Previously it had been necessary to supply a separate platform for each seat cushion, and the unit was not adaptable for seating between these units. The design of the applicant's invention not only permits seating at random in any location along a multiple seat unit, but also simplifies the construction by necessitating only a single platform for the unit.

Accordingly, it is an object of this invention to provide a spring seat construction of greater comfort than conventional designs.

Another object of this invention is to provide a cushion support unit of simplified low cost yet durable construction.

A further object of this invention is to provide a cushion support unit that provides a platform having lateral stability, a spring of durability and high strength, and which results in valuable clearance for frame bracing elements.

An additional object of this invention is to provide a spring support arrangement in which stress concentrations are reduced and a longer life is achieved.

A still further object of this invention is to provide a spring seat support of a platform type usable with sofas, love seats or the like which are longer than a chair intended for single occupancy.

Yet another object of this invention is to provide an improved clamping arrangement for springs to a cushion support platform.

An additional object of this invention is to provide a spring support arrangement in which different spring rates are obtained for front and rear springs manufactured from the same gauge wire.

These and other objects will become apparent from the following detailed description taken in connection with the accompanying drawing in which:

FIG. 1 is a top plan view, partially in section of a cushion support unit of this invention applied to a chair frame;

FIG. 2 is a transverse sectional view taken along line 2—2 of FIG. 1;

FIG. 3 is an enlarged fragmentary sectional view taken along the same plane as FIG. 2 illustrating the detailed

2

construction of the attachment of the lower leg of the rear spring;

FIG. 4 is an enlarged fragmentary plan view of the spring connection of FIG. 3;

5 FIG. 5 is an enlarged fragmentary sectional view taken along the plane of FIG. 2 illustrating the connection of the upper spring leg to the cushion support frame;

FIG. 6 is a sectional view similar to FIG. 2 of a modified form of the invention employing only rear springs;

10 FIG. 7 is a plan view similar to FIG. 1 but showing the invention as used for a multiple seat cushion unit;

FIG. 8 is a transverse sectional view taken along line 8—8 of FIG. 7;

15 FIG. 9 is a perspective view of one of the transverse rail units used in the design of FIGS. 7 and 8;

FIG. 10 is a fragmentary plan view of a spring unit arranged to reduce the lateral bending moment on the spring coil, and also employing a single clamp for securing the upper end of the spring coil;

20 FIG. 11 is a side elevational view of the arrangement of FIG. 10;

FIG. 12 is an enlarged perspective view of the clamp of FIG. 10;

25 FIG. 13 is a top plan view of a modification in which two springs and an interconnecting element are integrally constructed; and

FIG. 14 is a side elevational view of the design of FIG. 13.

With particular reference to FIGS. 1 through 5 of the drawing, the spring support unit 1 of this invention is shown in conjunction with the framework 2 of a chair or the like. This framework, which normally is constructed of wood, includes a front rail 3, a back rail 4, and a rear spring support rail 5 adjacent the back rail.

35 These rails are held in a spaced parallel relationship by side rails 6 and 7 that interconnect their ends.

A rectangular metal platform 8 is supported on the framework by means of front coil spring units 9 and 10

40 and rear coil spring units 11 and 12. These may be helical torsion springs with their axes substantially parallel to the front and rear framework rails. The platform 8 may simply consist of heavy gauge wire suitably bent to define a rectangular contour, with the ends of the wires joined together by means of a ferrule 14. The platform 8 serves to support the seat cushion, and accordingly there may be attached to its webbing, springs or the like (not shown).

45 The front coil spring units 9 and 10 may be substantially identical to the rear spring units 11 and 12. However, it generally is preferred to provide a different spring rate for the springs at the front from those at the rear of the device, with the stiffer spring located at the rear of the cushion support. One method of accomplishing this is by making the front and rear spring units of different materials. Alternatively, the turns of the front units 9 and 10 may be made of larger diameter than those of the rear spring coils. This is advantageous in that it allows the same materials to be used for all of the spring units, thereby simplifying production.

50 60 The spring coil units making up the spring pairs may be identical except that they are of opposite hand configuration. As seen in FIG. 2, the rear unit 11 includes an upper leg 16 inclining upwardly from coil 17 to the lower edge of the side portion 18 of platform 8. The upper leg of the spring unit 11 continues through a short span 19 adjacent the side element 18, and then extends around the corner of the platform with its end portion 20 beneath the rear rail 21 of the platform 8. Two clamping brackets 23 receive the segments of the platform and

65 70 the portions 19 and 20 of the upper leg of the spring, securing the spring to the platform. These brackets are somewhat in the shape of a figure 8 and may be spot

welded to the frame 8. This, plus the angular arrangement of the portions 19 and 20 of the spring leg, provides a rigid connection between the upper portion of the spring unit and the platform 8.

The lower portion 25 of the coil 17 inclines downwardly and to the rear, terminating in an end section 26 projecting inwardly substantially at right angles to the downwardly inclined portion 25. The leg 26 is secured to the support rail 5 by means of a bracket 27. The latter unit includes a cylindrical portion 28 positioned immediately forward of the rail 5 and from which projects an L-shaped base portion 29. The upper part of the base 29 lies on top of rail 5, while the end of this element contacts the rear vertical face of the rail 5. Nails 30 secure the base 29 to the rail 5. Leg 26 is received within a bushing 31, which may be of nylon, carried by the cylindrical portion 28.

The resulting construction is particularly advantageous in connecting the spring coil unit to the framework of the chair. The cylindrical portion 28 of the support member 27 for the bottom leg of the coil allows the portion 28 to pivot relative to the support as the spring is flexed. This free pivotal movement assures that significant bending forces are not imposed upon the lower leg of the rear spring, but are absorbed instead in the coil portion of it. This greatly increases the life of the spring element by avoiding fatigue failure in the lower leg portion of the coil unit. In the past it has been the practice to provide a rigid connection at the bottom of the spring coil. As a result, there has been a crystallization of the material in the lower leg of the coil in such prior designs after a period of use. This tendency is entirely avoided in the present invention by the use of the pivotal connection for the angular portion 26 of the lower leg of the spring coil unit.

The support element 27 is advantageous additionally by reason of the L-shaped configuration of the portion 29 extending from the cylindrical section 28. By the use of such an angular element, the support may be firmly secured to the rail 5 by means of nails without danger of the nails pulling free. The horizontally located nail will encounter primarily shear forces which it can readily absorb. This anchors the support member so that there is no tendency for it to be pried upwardly as downward forces are imposed on the outer cylindrical portion 28.

The front coil units 9 and 10 may be secured to the base 8 and to the framework of the chair substantially in the same manner as for the rear units. Thus, as seen in FIG. 2, the front unit 9 includes an upper leg 32 extending to the side portion 18 of the platform 8 and having an extension 33 beneath the forward portion 34 of the base. A pair of clamps 23 secures the upper leg in place to form a rigid connection with the platform.

Lower leg 37 inclines downwardly from coil 38 and has an angularly projecting portion 39 received in the cylindrical portion 28 of another support member 27. In this manner the lower leg of the front coil unit 9 is freely pivotal relative to the framework of the chair. Again, therefore, the advantage of the rotatable lower leg is achieved and fatigue failures are avoided.

The invention as illustrated in FIG. 6 is substantially the same as in the previously described embodiment with the exception that the front spring units 9 and 10 are omitted. In place of this, a front support rail 44 is added, located above the front rail 3 of the chair frame. A pair of brackets 27 pivotally receives the front element 21 of the seat platform and connects also to the rail 44. The necessary resilience for the seat cushion is provided by the rear coil units 10 and 11, while the front portion of the cushion platform is freely pivotal as the platform moves under load.

When modified in accordance with the design of FIGS. 7, 8 and 9, the invention is adapted to use with sofas, love seats, or other units where multiple seating is desired. This is accomplished by means of a single platform frame

46, which again may be of substantially rectangular construction and of adequate length to provide the seating capacity required. Front and rear spring coils 47 and 48 are provided at either end of the frame 46 and may be substantially identical to the corresponding coil units previously described. The coil units 49 and 50 that are positioned intermediate the ends of the framework also may be basically the same as in the previously described embodiment. There may be additional sets of intermediate coil units 49 and 50, depending on the length of the seating arrangement produced.

Transverse member 51 to which the upper legs 52 and 53 of the intermediate coils attach includes a curved central portion 54 at the ends of which are short straight segments 55 and 56. The latter portions are substantially in the plane of the cushion platform 46, at right angles to the front and rear rods 57 and 58 of this frame. From the segments 55 and 56 the member 51 inclines downwardly for lengths 59 and 60, and its ends 61 and 62 are bent at substantially right angles to the plane of the central portion 54. As a result of this arrangement, the ends 61 and 62 of member 51 may be attached to the front and rear members 57 and 58 of the platform frame 46 by means of clamp elements 23. The short straight segments 55 and 56 allow attachments of the upper legs 52 and 53 of the coil units to the transverse member by means of similar clamps. By being positioned above the ends 61 and 62, the portions 55 and 56 allow the upper spring legs to contact the under surface of the transverse member, and in the same plane engage under surfaces of the front and rear rails of the seat platform at their angled ends. This permits the use of spring units in the intermediate portion of the support structure that are the same as those positioned at the ends.

Of importance in the design of the transverse members 51 is the downwardly inclined portion 54 which constitutes the major length of the unit intermediate the front and rear rails of the seat platform. The downwardly convex contour of this part of the transverse member provides a clearance so that it is possible to position a seat cushion on the upper surface of the platform and to occupy the cushion at any point without causing the under surface of the cushion to contact a transverse member. The downward flexing of the cushion and its support will not result in engagement with the transverse member 51 due to the clearance resulting from the bowed portion 54. In the past it has been necessary to provide separate cushion support units for each part of a unit intended for multiple occupancy. Also, it has been impossible to sit with comfort on any part intermediate the support unit due to the inability of the cushion to flex in view of the transverse members of the separate support units. With the present design, however, there is a saving in time and materials during construction of the multiple cushion unit, and it is possible to sit with comfort at any location thereon.

An important variation in the design of the coil spring is illustrated in FIGS. 10 and 11. This construction has several advantages, producing stronger and more efficient springs, as well as stabilizing the platform. It also positions the coils further inside the frame to provide clearance for frame-bracing members which may be needed to increase the strength of the frame. It differs from the previously described spring units principally in the arrangement of the ends of the legs extending from the coils, which now are positioned to be parallel and point inwardly in opposite directions.

The coil unit 63 includes an upper leg 64 and a lower leg 65. The latter element projects laterally toward the frame structure from the end of the coil which is adjacent the side rail 67 of the platform for the seat cushion. The seat platform used with this coil arrangement may be either the type devised for a single cushion, such as that in FIGS. 1 and 2, or for multiple seating as in the version of FIG. 7. The upper coil leg 64 is at the opposite axial end of the coil 63 which is remote from the side rail 67.

The upper leg 64 projects from the coil in the same general direction as the lower leg 65, and upwardly to the seat platform rail 66, which is at right angles to the rail 67 to form a corner of the seat platform. The end of the upper leg 64 fits beneath the side rail 66 and is directed inwardly with respect to the coil, parallel to its axis. The distal portion 68 of the upper leg 64 extends around the corner defined by the junction of the rails 66 and 67. Hence, the end portion of the leg 64 is directed first axially inwardly with respect to the coil 63, extending from the end at which the leg 64 is located toward the opposite end. The distal portion 68 of the coil then fits around the corner between the rails 66 and 67, being therefore substantially L-shaped and terminating beneath the rail 67. The end of the leg 64 is secured to the rails 66 and 67 by means of a clamp 71.

The bottom leg 65 of the coil unit 63 terminates in an end portion 69, which is at right angles to the remainder of the leg 65, and extends inwardly with respect to the coil. A clamp 70 pivotally secures the end 69 of the bottom leg 65 to the frame structure. This will be to either the front or rear rail of the frame, depending upon which is adjacent the coil unit 63. In the usual instance there are four of the coils 63, located at the four corners of the frame structure. Alternatively, there may be only two of the spring units 63 located at the rear of the unit in a manner generally similar to the embodiment of FIG. 6.

Thus, the end of the leg 64 extends inwardly with respect to the coil in one direction, while the end of the leg 65 extends inwardly in the opposite direction, so that the end legs of the coil in effect cross at their distal portions. This coil design offers the significant improvement of rendering the seat platform much more stable than the previously described embodiments. By extending the end legs in opposite directions, inwardly with respect to the coil of the spring, the springs become much more resistant to lateral forces. Side sway of the platform is prevalent with designs that do not incorporate this feature. However, in the arrangement of FIGS. 10 and 11, such undesirable lateral instability is eliminated. Hence, the seat becomes much more comfortable, as well as being supported on a spring of greater strength and durability.

As a result of the construction of FIGS. 10 and 11, forces tending to twist the coil are balanced and there is an absence of distortion of the coil as the spring is flexed. There are no large, unsupported twisting moments imposed upon the coil. As a result, the coil is stronger, better maintains its shape, operates more efficiently, and has an increased life.

Another advantage realized from the construction of FIGS. 10 and 11 is that the coils become positioned further from the corners of the frame than in the previous embodiments. By extending the end legs in opposite directions and inwardly with respect to the coil, the coil then becomes spaced an appreciable distance from the side frame member adjacent the side rail 67. Otherwise, if constructed as shown in FIG. 1, the coil would be quite close to this frame element, as are the coils 9, 10, 11 and 12 with respect to the members 6 and 7. This added lateral spacing gives an advantageous clearance for corner blocks, rocker blocks and other frame-bracing members which frequently must be incorporated in the frame construction.

As the coil 63 is dimensioned, the bottom leg 65 is longer than the top leg 64 of the coil. When this is true for the rear coil units, it causes the cushion platform to move in a more nearly vertical direction than otherwise is the case, eliminating any tendency for it to shift laterally. This proportioning may be used to advantage for any of the rear coils of this invention.

Also shown in FIGS. 10 and 11, as well as in the perspective view of FIG. 12, is a clamp member 71 for securing the upper spring leg to the frame. This accomplishes the attachment by a single member having end 75

sections 72 and 73 that receive both the seat platform frame and the spring leg. The end portions are formed to define partial cylinders 74 and 75, and 76 and 77. The two cylindrical segments in each set join each other, and 5 the lower portions include splits 78 and 79 to permit assembly and clamping. The pairs of downwardly extending tabs 75a and 77a on the lower partial cylinder sections may be tack welded together when the clamps are installed. The two end portions are rigidly connected by an intermediate strap 80. This single-piece 10 clamp merely is contracted around both the rail of the platform and the spring leg at both its ends to form the necessary attachment. This securely holds the spring leg without permitting movement of it and without requiring 15 the clamping member to be spot welded to the platform as in the previously described embodiment. Thus, a more trouble-free connection is achieved and assembly time is reduced.

Single unit construction also may be used for the front 20 and rear springs and interconnecting transverse piece. This may be seen in FIGS. 13 and 14 where front and rear springs 81 and 82 are integral with interconnecting element 83. This transverse portion may be bowed downwardly to provide a clearance for downward movement 25 of a seat cushion similarly to that afforded by member 51. The upper legs 84 and 85 of the two springs extend laterally at segments 86 and 87 which join the opposite ends of element 83. Portions 86 and 87 are adapted to engage the underside of the front and rear portions of 30 the platform to which they are clamped in the usual manner. Preferably, they are substantially parallel to the axes of the spring coils (which are parallel to each other) and extend from one end toward the other. The lower legs 88 and 89 include end segments 90 and 91 which 35 are for attachment to the frame of the seating unit. These end portions also are parallel to the coil axes, each projecting inwardly from one end of the coil toward the other for balancing the twisting forces on the coil.

The resulting construction allows one simple part to 40 replace the three separate pieces 49, 50 and 51. Only two clamps are needed in connecting the upper portion to the platform. This means a saving in both materials and assembly time, and provides a reliable maintenance-free structure. While intended primarily for use intermediate 45 the ends of a multiple cushion unit, it also may be employed to advantage at the end portions as well. By omitting the straight end segments 55 and 56 of member 51, transverse element 83 provides a clearance beneath a seat cushion for the full depth of the platform, which 50 could not be accomplished where the portions 55 and 56 are present.

The foregoing detailed description is to be clearly understood as given by way of illustration and example only, the spirit and scope of this invention being limited 55 solely by the appended claims.

I claim:

1. A seat cushion support comprising
a platform means adapted to support seat cushion
means,
a fixed structure,
and spring means interconnecting said platform means
and said fixed structure,
said spring means including at least two spring
units for supporting said platform means with
respect to said fixed structure,
each of said units including
a helical coil portion,
an upper leg
and a lower leg,

said upper leg extending laterally from
one end of said helical coil portion to
a position adjacent said platform means
and including a portion extending from
said position inwardly with respect to
the axis of said coil,

- said lower leg extending laterally from the opposite end of said coil means to a position adjacent said fixed structure and including a portion extending from said position inwardly with respect to the axis of said coil, 5
said portions of said upper and lower legs being substantially parallel, and extending in opposite directions, 10
means rigidly connecting said portion of said upper leg to said frame, 15
and means pivotally connecting said inwardly extending portion of said lower leg to said fixed structure.
2. A device as recited in claim 1 in which said platform means includes 15
a front and
a rear portion,
and said spring means includes
spring units adjacent said front portion 20
and spring units adjacent said rear portion,
said spring units being constructed of a substantially identical material
with the helical coil portions of said spring units adjacent said front portion being of larger diameter than that of the helical coil portions adjacent said rear portion of said platform means. 25
3. A device as recited in claim 2 in which said lower legs of said spring units adjacent said rear portion of said platform means are longer than the upper legs of said spring units adjacent said rear portion. 30
4. A device as recited in claim 1 in which said platform means is a substantially rectangular wire frame unit, 35
said spring units including at least two front and two rear coils,
the upper leg of each of said coils being adjacent the under surface of said wire frame and disposed at a corner thereof,
said upper leg having a distal end projecting laterally from said inwardly extending portion toward said coils to provide said upper leg with a substantially L-shaped distal portion, 40
said means rigidly connecting said upper leg to said platform means including means to clamp said L-shaped distal portions beneath the corners of said wire frame. 50
5. A device as recited in claim 1 in which said means pivotally connecting said inwardly extending portions of said lower legs to said fixed structure includes
a substantially cylindrical element for each of said lower legs, 55
and a bushing within each of said cylindrical elements,
said inwardly extending portions of said lower legs being rotatably received within said bushings. 60
6. A cushion-supporting device comprising
a platform adapted to support seat cushion means, 65
a framework, and means resiliently connecting said platform to said framework,
said platform including a front and a rear elongated member,
and spaced side members interconnecting said elongated members, 70
said framework including spaced front and rear rails,
said resilient means including at least one spring unit adjacent the rear elongated member of said platform at either side thereof, 75

- each of said spring units including a helical coil, 5
said helical coils having their axes substantially parallel to said front and rear elongated members,
an upper leg extending laterally from said coil to the under surface of said platform, 10
said upper leg having an inwardly extending portion substantially parallel to the adjacent rear elongated member of said platform and directed inwardly with respect to the axis of said coil,
said inwardly extending portion having an angled end extending around the corner of said platform to the adjacent side member of said platform, 15
means rigidly connecting said upper leg to said platform, 20
a lower leg extending laterally from said coil to said rear rail of said framework,
said lower leg having a distal end substantially parallel to said rail and extending axially inwardly with respect to said coil, 25
said inwardly extending portion of said upper leg and said distal end of said lower leg being thereby substantially parallel and extending in opposite directions, 30
and cylindrical receptacle means pivotally connecting said ends of said lower legs to said rail, 35
said ends of said lower legs being axially aligned with said cylindrical receptacles.
7. A cushion-supporting device comprising
a substantially rectangular frame
having substantially parallel front and rear rails, 40
and a duality of side rails interconnecting said front and rear rails thereby to define four corners,
a platform adapted to support a cushion, 45
said platform including a substantially rectangular element having front and rear elements interconnected by a duality of side elements, 50
and a spring unit at each corner of said frame interconnecting said frame and said platform,
each spring unit including
a helical coil having its axis substantially parallel to said front and rear rails, 55
a lower leg extending laterally from said coil at the end thereof juxtapositional the side rail at the corner where said coil is located to the adjacent one of said front and rear rails, 60
said lower leg having a distal end extending inwardly with respect to said coil and substantially parallel to the axis thereof, 65
and an upper leg extending laterally in the same general direction as said lower leg from the opposite end of said coil to the adjacent one of said front and rear platform elements, 70
said upper leg having a distal end including a portion extending inwardly with respect to said coil and substantially parallel to the axis thereof, 75
said distal ends thereby being substantially parallel and extending in opposite directions, 80
a bearing for each of said ends of said lower legs carried by said front and rear rails, and a clamp rigidly connecting said distal ends of said upper legs to said rectangular element. 85
8. A device as recited in claim 7 in which said distal ends of said upper legs engage the lower surface of said rectangular wire element, 90
said distal ends including outer portions extending

- at right angles to said inwardly extending portion of said upper leg and beneath the adjacent side element of said rectangular element, said clamp securing each of said distal ends of said upper legs to said adjacent side element, and to the adjacent one of said front and rear elements of said rectangular element.
9. A device as recited in claim 7 in which said clamp for connecting said distal ends of said upper legs to said rectangular element includes receptacle opposite end portions for receiving and gripping said element and spring leg one above the other, said end portions being disposed at right angles to each other,
- said clamp further having a rigid intermediate portion interconnecting said end portions and maintaining said portions in said angular relationship with each other.
10. A cushion-supporting device comprising a structural framework, a platform adapted to support cushion means, and means resiliently connecting said platform to said framework,
- said last mentioned means including spring units at the ends of said platform and at least one spring unit intermediate the ends of said platform,
- said intermediate spring unit including a dual-

15 10

11. A device as recited in claim 10 in which portions of said elongated element between said upper legs are below the ends of said upper legs.

ity of coil means disposed one at either end thereof, each of said coil means including a helical torsion spring having a lower leg connected to said framework, an upper leg connected to said platform, and an elongated element interconnecting said upper legs and integral therewith, said upper and lower legs each including an end portion in spaced parallelism with the axis of its spring and extending inwardly from one end of the spring toward the other.

15

11. A device as recited in claim 10 in which portions of said elongated element between said upper legs are below the ends of said upper legs.
